Primary Examiner — Ian Simmons*Assistant Examiner* — Charles Hanson(74) *Attorney, Agent, or Firm* — McCracken & Frank LLC(57) **CLAIM**

The ornamental design for a pull rod of a luggage, as shown and described herein.

DESCRIPTION

FIG. 1 is the front view of the design.

FIG. 2 is the back view of the design.

FIG. 3 is the left view of the design.

FIG. 4 is the right view of the design.

FIG. 5 is the top view of the design.

FIG. 6 is the bottom view of the design.

FIG. 7 is the front view of the design when the pull rod is pulled out.

FIG. 8 is the back view of the design when the pull rod is pulled out.

FIG. 9 is the left view of the design when the pull rod is pulled out.

FIG. 10 is the right view of the design when the pull rod is pulled out.

FIG. 11 is the front view of the design when the pull rod is pulled out further; and,

FIG. 12 is the back view of the design when the pull rod is pulled out further.

The broken lines in FIGS. 11 and 12 are included to indicate a break along the length of the lower section of the pull rod because it is longer than the space available. These broken lines form no part of the claimed design.
